UNITED STATES PATENT OFFICE.

ADOLPH RIPPEN, OF READING, PA., ASSIGNOR TO WILLIAM M. GRISCOM,
MATTHAN HARBSTER, AND WILLIAM HARBSTER, OF SAME PLACE.

APPLE-PARER.

SPECIFICATION forming part of Letters Patent No. 233,023, dated October 5, 1880.

Application filed July 2, 1880. (Model.)

To all whom it may concern:

Be it known that I, ADOLPH RIPPEN, a citizen of the United States, residing in Reading, in the county of Berks and State of Pennsylvania, have invented certain Improvements in Apple-Parers, of which the following is a specification.

My invention relates to certain devices whereby the paring-knife, after completing the paring operation, is removed from contact with the apple and brought back to position for commencing to pare another apple, the main objects of my invention being to provide for the complete paring of the apple, to insure compactness of the parts, and to reduce the size and weight of the device, so as to facilitate transportation and storage.

In the accompanying drawings, Figure 1, Sheet 1, is a perspective view of my improved apple-parer; Fig. 2, Sheet 2, a vertical section; Fig. 3, Sheet 3, a plan view of the same, partly in section; Fig. 4, a sectional plan on the line 1 2, Fig. 2; Fig. 5, a sectional plan on the line 3 4, Fig. 2, with the parts in different positions from those shown in Fig. 3; Fig. 6, Sheet 1, a sectional plan, showing a modification of my invention; Fig. 7, a vertical section of Fig. 5; and Fig. 8, Sheet 2, a detached view of part of the device.

A is the main standard or frame of the machine, which has at the lower end the usual jaws and screw whereby it is clamped to the table or other support, the standard also having bearings for the turn-table, operating-shaft *a*, and fork-shaft *a'*, and being furnished with a stud for the knock-off lever B, the fork-shaft and turn-table shaft being geared together by the cog-wheel *b* and pinion *b'* in the usual manner.

Projecting from the standard A is a bracket, D, and secured to or forming part of the latter is a vertical stud, *d*, to which are pivoted two turn-tables, E and F, and a frame, G, the hub of said frame being confined between the lower turn-table, E, and the elongated hub *e* of the upper turn-table, F, the latter being retained in its proper vertical position by a cover-plate, H, secured to a lug on the standard A.

The turn-table E is provided with an annular series of inclined teeth, and the turn-table

F has an annular series of inclined slots, the pinion *a'* on the shaft *a* gearing with these teeth and engaging with the slots, so as to revolve the turn-tables in opposite directions. The inclining of the teeth and slots of the turn-tables is rendered necessary by the fact that the operating-pinion *a'* is not in line with the center of said turn-tables.

The outer end of the frame G projects beyond the turn-tables E F, and has a pivot-pin, *f*, to which is hung the arm J, carrying the paring-knife, said arm being acted upon by a coiled spring, *g*, the tendency of which is to throw the knife inward over the turn-table F and against the apple placed on the fork.

An arm, *i*, on the knife-carrying arm J, has a pin, *i'*, which is adapted to an opening in the outer end of a plate, M, the inner end of which is slotted and embraces the hub *e* of the turn-table F, the plate also having a projection, *m*, and a rib, *s*, the projection *m*, under the circumstances described hereinafter, engaging with a lug, *n*, on the cover-plate H, and the rib *s* being acted upon by a lug, *t*, on the turn-table F.

In the periphery of the turn-table E is formed an inclined recess, *v*, which terminates in a shoulder, *w*; and on the under side of said turn-table E is a cam, *p*, which acts on the short arm of the bell-crank lever R for operating the knock-off bar.

The operation is as follows: When the machine is at rest the parts are in the positions shown in Figs. 3 and 4, the knife-arm J resting in the recess *v* in contact with the shoulder *w*. The turn-table E is free to be turned backward in the direction of the arrow 1 to the extent of the length of the recess *v* without operating the knife-carrying arm, so that when the machine is started in the right direction—that is to say, in the direction of the arrow 2—the fork-shaft and the apple carried by the fork will make a full revolution before the knife commences to move, thereby insuring the complete paring of the apple close up to the stem.

When the shoulder *w* comes into contact with the arm J the latter is caused to rotate with the turn-table E, carrying with it the frame G and plate M, and this movement of

rotation is continued until the knife has made a half-revolution and finished the paring of the apple. The projection *m* on the plate *M* then comes into contact with the lug *n* on the cover-plate *H*, and the movement of the turn-table *E* continuing, the plate *M* is moved outward so as to free the arm *J* from the control of the shoulder *w* of the turn-table *E* and bring the rib *s* of the plate *M* into the path of the lug *t* on the turn-table *F*, as shown in Fig. 5, the movement of the arm *J* carrying the cutting-knife away from the apple. As the turn-table *F* is moving in the direction of the arrow 1 a movement in the same direction is imparted to the plate *M*, and to the frame *G* and knife-arm *J*, the latter bearing on the periphery of the turn-table *E*, so as to maintain the cutting-knife free from contact with the apple during this movement of retraction. The backward movement continues until the arm *J* is at liberty to enter the recess *v* of the turn-table *E*, this movement serving to free the rib *s* of the plate *M* from the control of the rib *t* of the turn-table *F*, and bringing the parts again into the positions shown in Figs. 3 and 4 prior to a repetition of the operation. It should be understood, however, that before the parts reach this position the cam *p* on the turn-table *E* has actuated the bell-crank lever *B* so as to operate the knock-off arm and thrust the pared apple from the fork. When the inward movement of the arm *J* is resisted by contact of said arm with the periphery of the turn-table *E*, as above set forth, the resistance to the movement of rotation of the frame *G* due to the friction between the arm *J* and the turn-table is exerted at such a distance from the center or pivot on which the said frame *G* turns as to be disadvantageous; hence in making a light-running machine I prefer to adopt the construction shown in Figs. 6 and 7, in which the inward movement of the knife-arm *J* is resisted by a segmental rib, *y*, formed on the turn-table *E*, this rib engaging with a pin, *x*, projecting from the plate *M*, which is connected to the arm *J*. In this case, owing to the proximity of the rib *y* to the pivot of the frame *G*, the friction can be overcome with less effort than in the machine shown in Figs. 1 to 5.

By adopting the means above described for operating the knife-carrying arm I am enabled to make a machine which is very light and compact and can be packed into small compass for transportation—a fact of considerable importance in machines intended for the export trade.

The arrangement of the cam *p* on the bottom of the turn-table *E*, instead of on the periphery of the same, as usual, and the use of a bell-crank lever in connection with the cam for

operating the knock-off arm, aid in reducing the size of the machine, and the location of the driving-pinion *a* on one side of the center of the turn-tables *E* *F* is also of some value in this respect.

I claim as my invention—

1. The combination, in an apple-parer, of an apple-holding fork and rotating mechanism, a swinging frame carrying the knife-arm, two turn-tables, each capable of making a complete revolution, devices for rotating the turn-tables simultaneously in opposite directions, and devices, substantially as described, whereby the frame carrying the knife-arm is controlled first by one turn-table and then by the other, all substantially as set forth.

2. The combination, in an apple-parer, of a rotating fork, a swinging frame carrying the knife-arm, a rotating turn-table for carrying the frame and knife-arm forward, another turn-table rotating in an opposite direction and serving to carry the knife-arm backward, devices for shifting the control of the frame from one turn-table to the other, and devices, substantially as described, whereby the knife-arm is thrust outward and the knife kept free from the apple during its backward movement, as set forth.

3. The combination, in an apple-parer, of the swinging frame carrying the knife-arm, the turn-table *E*, having a shoulder, *w*, the turn-table *F*, having a lug, *t*, the plate *M*, connected to the knife-arm and having a projection, *m*, and rib *s*, the cover-plate *H*, having a rib, *n*, and means for rotating the turn-tables *E* and *F* in opposite directions, all substantially as specified.

4. The combination of the swinging frame *G*, the knife-arm *J*, the turn-table *E*, having a shoulder, *w*, and segmental rib *y*, the turn-table *F*, having a lug, *t*, the frame *M*, having a projection, *m*, rib *s*, and pin *x*, the cover-plate *H*, having a lug, *n*, and means for rotating the turn-tables *E* *F*, as set forth.

5. The combination of the frame *G* and the knife-arm *J* with a turn-table, *E*, having a shoulder, *w*, and a recess, *v*, adjacent thereto, as set forth.

6. The combination of the frame *A*, having a bracket, *D*, with stud *d*, the turn-tables *E* *F*, and frame *G*, adapted to said stud, and the cover-plate *H* for retaining them in position thereon, as specified.

In testimony whereof I have signed my name to this specification in the presence of two subscribing witnesses.

ADOLPH RIPPEN.
